UNITED STATES PATENT OFFICE.

WILLIAM G. LUCAS, OF MCKEESPORT, PENNSYLVANIA.

TIE AND RAIL-FASTENER.

1,005,050.

Specification of Letters Patent.

Patented Oct. 3, 1911.

Application filed April 20, 1911. Serial No. 622,312.

To all whom it may concern:

Be it known that I, WILLIAM G. LUCAS, a citizen of the United States of America, residing at McKeesport, in the county of 5 Allegheny and State of Pennsylvania, have invented certain new and useful Improvements in Ties and Rail-Fasteners, of which the following is a specification, reference being had therein to the accompanying 10 drawing.

This invention relates to ties and rail fasteners, and has for its object to provide a metallic tie for supporting rails or the confronting ends thereof, and to provide the 15 tie with novel fasteners for retaining the rails upon the tie.

Other objects of my invention are to combine concrete and metal in the form of a tie that can be easily installed upon the 20 ballast of a roadbed and tamped, and to use fasteners in connection with the tie that will prevent lateral and vertical displacement of the rails of a track.

Further objects of my invention are to 25 provide a metallic reinforced tie that is simple in construction, strong and durable, and to accomplish the above results by a mechanical construction consisting of comparatively few parts easy to assemble and 30 maintain in order.

With the above and other objects in view, the invention resides in the novel construction, combination and arrangement of parts to be hereinafter specifically described and 35 then claimed.

Reference will now be had to the drawing, wherein like numerals of reference designate corresponding parts throughout the several views, in which:—

40 Figure 1 is a perspective view of ties and fasteners in accordance with this invention, Fig. 2 is an enlarged side elevation of a portion of one of the ties, partly broken away and partly in section, Fig. 3 is a plan of the 45 same, Fig. 4 is an end view of the tie, Fig. 5 is an enlarged perspective view of one of the rail chairs, Fig. 6 is a perspective view of a detached fastener, and Fig. 7 is a side elevation of a portion of the chairs of the 50 rail.

The tie consists of two channel-bars, four rail chairs, four fasteners and a concrete body, together with the fastening means employed for connecting these parts together.

The chairs are identical in construction,

each chair comprising base flanges 1, a web 2 and a top flange 3 constituting a rail seat. The web 2 of each chair has longitudinal oppositely disposed ribs 4 adjacent to the 60 top flange 3, and the chairs at the confronting ends of the webs 2 thereof are slotted, as at 5 directly beneath the ribs 4, and these ribs, the web 2 and the top flange 3 are cut away upon an angle, as at 6, the 65 cut in the top flange 3 forming a slot 7.

The base flanges 1 of the chairs are provided with longitudinal seats 8 for the lower flanges 9 of channel-bars 10, these bars having the upper flanges 11 thereof supporting 70 the top flanges 3 of the chairs. The channel-bars 10 rest against the outer edges of the ribs 4 and said bars are connected to the chairs by transverse bolts 12 and nuts 13.

The channel-bars intermediate the ends 75 of the tie are connected by transverse rods or other fastening means 14 and arranged longitudinally between said channel-bars are metallic reinforcements 16 within a concrete body 17. The ends of the concrete body 17 80 protrude into the space between the webs 2 of the inner chairs and the walls of the bars 10, and to reinforce this concrete body, expanded metal, twisted rods or similar structures can be employed.

The rails to be supported by the tie comprise heads 15, webs 18 and a base 19, the base being of a less width than the heads 15 and adapted to rest upon the chairs at the meeting or confronting edges thereof.

The fasteners employed for holding the rail consists of reinforced splice bars 20 adapted to brace the inner and outer sides of the rail and support the head 15 thereof, these splice bars resting upon the chairs of 95 the tie. The fasteners are provided with depending locking members 21 adapted to engage in the slots 7 of the top flanges 3 of the chairs. The members 21 have vertical confronting sides and inclined sides 22 to 100 engage the angular end of the web 2 and the ribs 4, said members also having lips 23 which engage in the slots 5, these lips preventing vertical displacement of said members while the walls of the slots 7 prevent 105 longitudinal displacement.

The tie can be made up with the outer chairs detached, and after the inner fasteners have been placed in position, the rails can be placed upon the tie, the outer fasteners placed in the outer chairs and the chairs placed between the ends of the channel-bars 110

of the tie. The outer bolts can then be placed in position and the rails will be firmly held.

From the foregoing it will be observed that I have devised a metallic tie that can be manufactured at a comparatively small cost and advantageously used in connection with steam and industrial railways. The rails can be rolled at a less cost than the present type of rail, and as the use of spikes and clips is obviated, it is apparent that the expense of maintenance is reduced to a minimum.

While in the drawing there is illustrated a preferred embodiment of the invention, it is to be understood that the structural elements thereof are susceptible of such changes as fall within the scope of the appended claims.

20. What I claim is:—

1. A tie comprising inner and outer chairs forming rail supports, channel-bars connecting said chairs, a concrete body arranged between said bars, and rail fasteners held 25 between the confronting ends of said inner and outer chairs.

2. A tie comprising inner and outer chairs, channel-bars arranged throughout the length of said tie and connected to said chairs, a 30 metallic reinforced concrete body arranged between said bars, and rail fasteners held by the confronting ends of said inner and outer chairs.

3. A tie comprising inner and outer chairs 35 forming rail supports, longitudinal channel-bars connecting said chairs, a metallic reinforced concrete body arranged between said bars, fasteners mounted upon said chairs, and depending members carried by said 40 fasteners and adapted to engage in said chairs at the confronting ends thereof.

4. In a tie, inner and outer chairs forming the ends of the tie, longitudinal channel-bars connecting said chairs, a metallic 45 reinforced concrete body arranged between said bars and the innermost chairs, said chairs having the confronting ends thereof slotted, rail fasteners mounted upon said chairs, depending members carried by said 50 fasteners and adapted to engage in the slots of said chairs, and means adapted to detachably hold said outer chairs in engagement with said inner chairs.

5. In a railway tie, the combination with 55 a pair of spaced channel members, of rail chairs each comprising a base flange provided with longitudinal seats for the base flanges of the channel members, said rail chairs disposed between the channel members at the ends of the latter and having top flanges overlying the top flanges of the channel members and constituting rail seats.

6. In a railway tie, the combination with 60 a pair of spaced channel members, of rail chairs each comprising a base flange pro-

vided with longitudinal seats for the base flanges of the channel members, said rail chairs disposed between the channel members at the ends of the latter and having top flanges overlying the top flanges of the channel members and constituting rail seats, and a concrete filling between the channel members having channel-connecting members embedded therein. 70

7. In a railway tie, the combination with 75 a pair of spaced channel members having their flanges projecting outwardly, of rail chairs disposed between the channel bars at the ends of the latter and embodying base flanges on which the channel bars are 80 seated at the ends of the latter, said rail chairs also embodying top flanges overlying the top flanges of the channel bars and constituting rail seats, and bolts securing the channel bars and rail chairs together. 85

8. In a railway tie, a pair of spaced channel members, a pair of rail chairs mounted between the channel members at the ends of the latter, each rail chair embodying a base flange forming seats for the base flanges of 90 the channel members at the ends of the latter, each rail chair also having a top flange overlying the top flanges of the channel members and forming a rail seat, means carried by said rail chairs for holding the 95 channel members in spaced relation, and means for securing the channel members and rail chairs together.

9. In a railway tie, a pair of spaced channel members, a pair of rail chairs mounted 100 between the channel members at the ends of the latter, each rail chair embodying a base flange forming seats for the base flanges of the channel members at the ends of the latter, each rail chair also having a top flange 105 overlying the top flanges of the channel members and forming a rail seat, means carried by said rail chairs for holding the channel members in spaced relation, means for securing the channel members and rail 110 chairs together, and a concrete filling between said channel members.

10. In a railway tie, a pair of spaced channel members, and a pair of rail chairs, each rail chair comprising a body or web, a 115 base flange, and a top flange, the base flange having seats for the end portions of the channel members and the top flange overlying the channel members and forming a rail seat, and rail securing means detachably connected to said chairs.

11. In a railway tie, a pair of spaced channel members, rail chairs at the ends of the members, said chairs supporting the rails and also constituting supports for the channel members at the ends of the latter, and means connecting the channel members and chairs together. 125

12. In a railway tie, a pair of spaced channel members, rail chairs at the ends of the 130

members, said chairs supporting the rails and also constituting supports for the channel members at the ends of the latter, means connecting the channel members and chairs together, and a concrete filling between said channel members.

13. In a railway tie, a pair of spaced channel members and a pair of rail chairs constituting both a support for the rail and a support for the channel members at the ends of the latter, said chairs provided with means to hold the channel members in spaced relation, and means for securing the channel members and chairs together.
14. In a railway tie, a pair of spaced chan-

nel members and a pair of rail chairs constituting both a support for the rail and a support for the channel members at the ends of the latter, said chairs provided with means to hold the channel members in 20 spaced relation, means for securing the channel members and chairs together, and a concrete filling between said channel members.

In testimony whereof I affix my signature in the presence of two witnesses.

WILLIAM G. LUCAS.
